UNITED STATES PATENT OFFICE.

SILVIO CAROSELLI, OF DETROIT, MICHIGAN.

NECKTIE.

1,282,042.

Specification of Letters Patent.

Patented Oct. 22, 1918.

Application filed June 24, 1918. Serial No. 241,464.

To all whom it may concern:

Be it known that I, SILVIO CAROSELLI, an Italian subject, residing at Detroit, county of Wayne, State of Michigan, have invented 5 a certain new and useful Improvement in Neckties, and declare the following to be a full, clear, and exact description of the same, such as will enable others skilled in the art to which it pertains to make and use the 10 same, reference being had to the accompanying drawings, which form a part of this specification.

My invention relates to an improvement in ties shown in the accompanying drawings and more particularly pointed out in the following specification and claim.

It is well known that "four-in-hand" ties as ordinarily constructed, are lined with a loose padding of canton flannel or other suitable material to give the tie, when worn, the desired "fullness" necessary for a pleasing effect, and it is also well known that the lining, after the tie has been worn several times, frequently becomes misplaced beneath 25 its covering of silk, producing a "bunched-up" appearance which it is difficult to remove by pressing.

It is also well known that when a tie is pressed on its face the silk is often injured 30 and the appearance of "newness" destroyed.

It is therefore one of the objects of this invention to provide a construction in which the tie may be "opened" down the back in order that it may be pressed from the inside,—means being provided to detachably secure the folds of the tie together in such manner as to give the folds the appearance of being permanently connected together as 35 ordinarily constructed.

Another object of the invention is to secure the lining to the tie by sewing its edges to the edges of the tie proper. Thus the lining cannot become misplaced through wear and when the tie is "opened" for pressing, 40 the pressing iron may be applied directly to the lining and thus the tie proper is protected from contact therewith. As the tie, however, may be pressed from the inner face of the material it is not apt to be injured 45 through contact with the pressing iron on portions not protected by the lining.

With the foregoing and other objects in

view which will appear as the description proceeds, the invention resides in the combination and arrangement of parts and in 55 the details of construction hereinafter described and claimed, it being understood that changes may be made in the precise embodiment of the invention as herein disclosed without departing from the spirit of the 60 same.

In the accompanying drawings forming part of this specification:—

Figure 1 is an elevation of a four-in-hand tie as viewed from the back,—showing the 65 usual folded overlapping edges at the back of the tie "opened" to expose the inclosed lining or padding,—sewed to the edges of the folded portions.

Fig. 2 is elevation of the tie shown in Fig. 1 showing the detachable edges folded as 70 they would appear when secured together for wear.

Referring now to the letters of reference placed upon the drawings:

A, denotes a "four-in-hand" tie of usual 75 shape, the overlapping edges B, B at the enlarged ends of the tie being detachably connected together at the back by suitable fastening devices C.

The overlapping parts of the relatively narrow band D, connecting the end portions are preferably sewed together as ordinarily constructed, but if desired the overlapping edges of the tie may be detachably connected 85 together from end to end.

E, indicates a lining of canton flannel or other suitable material, sewed to the tie adjacent to its outer edges.

Having indicated the several parts of the 90 tie by reference letters its construction will be readily understood. When the tie becomes creased or rumpled it may be readily restored to its original smooth condition by disconnecting the folded edges at the back of 95 the tie so as to lay bare the lining within. The tie may then be pressed without danger of injuring the fabric or displacing the lining by applying the iron directly to the lining, the wrinkles in both the tie and its 100 lining being thus easily smoothed out. As the lining is sewed to the edges of the tie, instead of being loosely inserted as ordinarily constructed, it cannot become dis-

placed and therefore the pressing of the tie is a simple operation to perform.

Having thus described my invention what I claim is:

- 5 A tie of the four-in-hand type, an inner lining sewed along its edges to the edges of the tie, said tie and lining folded longitudinally so as to overlap each other adjacent to the inner face of the body of the tie,

and means for detachably securing said folded portions together.

In testimony whereof, I sign this specification in the presence of two witnesses.

SILVIO CAROSELLI.

Witnesses:
